RECOVER PACK FOR TENNIS BALLS

Maurice M. Bayon, New Orleans, La.

Application September 19, 1934, Serial No. 744,737

1 Claim. (Cl. 273—61)

This invention relates to apparatus and material for recovering used tennis balls.

It is well known that tennis balls through use become worn and the covers smooth, in which case the effectiveness of the ball is greatly lessened. The stroking of the ball becomes more difficult and results in weird shots and in unexpected bounces. In many cases, however, the "centers" are in perfect condition and capable 10 of satisfactory play.

The principal object of my invention is to provide means for recovering or resurfacing satisfactory "centers" so that the life of the ball can be prolonged with a substantial savings in expense. Such balls can readily be used for practice and for ordinary play without the necessity, as has heretofore been the practice, of throwing away worn balls with good "centers". The greatest demand for such balls will be with tennis clubs and organizations. However, there is nothing to prevent individuals following the teachings of my invention and utilizing the same.

Another object of the invention is to provide fabric covers, preferably of felt, cut to fit the "centers" either with straight sides or resembling a "figure 8". These covers of the usual shape will come to the coach or user ready for application to the "centers".

A further object of the invention is to provide a recovering unit having the edges coated with a preparation that retains its vulcanizing properties more or less indefinitely so as to make practicable the application of the re-covering unit to the stripped center of the ball for a long period of time after the prepared re-covering unit has left the factory.

Heretofore, it has not been practical to recover the "centers" because various forms of new rubber in the nature of "latex" have been used which dry quickly in the air, necessitating the immediate application of the covers to the "centers" with elaborate equipment. This is particularly true as far as the edges of the strips are concerned, it being highly desirable that these edges be adhered together to prevent the curling of the covers.

Still another object of the invention is to provide the covers in packs ready for attachment to the "centers" with a cold rubber cement placed on the face and along the edges of the strips, of such nature that exposure to the air does not affect the vulcanizing properties of the cement.

Other objects will be disclosed in the specification and claim forming a part of this application.

In the drawing:

Figure 1 is a top plan view of the rubber "center" having above and below the same a semi-cover;

Figure 2 is a vertical section taken on line 2—2 of Figure 1;

Figure 3 is a vertical section of the heating or vulcanizing mold with a ball therein; and

Figure 4 is a perspective of a plurality of covers ready for application to the "centers".

in the drawing, in which similar parts are 10 designated by like numerals:

Numerical 5 refers to a "center" from which the former cover has been removed. The re-covering patches comprise a pair of similarly shaped blanks 6 and 7 adapted to encase the "center". 15 Many different methods have been employed in securing the covers to the "center", the preferred form at the present time being the use of cement. The securing of the edges of the covers has also been a constant problem, stitches sometimes being used, and the cement on the face of the cover has been depended upon to prevent the edges curling.

The present invention proposes to apply cold cement 8 to the inner face of the covers 6 and 7 25 and on the edges 9, the term "cold cement" being a trade designation for a rubber cement which as has been previously stated retains its vulcanizing property notwithstanding its prolonged exposure to air. The cover pieces 6 and 7 will be 30 dispensed in packs, preferably of ten or a dozen, as shown in Figure 4, congruently piled.

A mold or heating apparatus 10 is shown in Figure 3 for receiving the "centers" with the covers 6 and 7 in place.

As actually used, the coach or tennis attendant upon the old covers becoming worn, will strip the same from the balls. Two of the ready-prepared patches 6 and 7, having cold cement or other vulcanizable material along the edges 9 and 40 on one face of each strip, will then be placed around the center, the cement covered surfaces and the center having first been cleaned with benzine, gasoline, or similar products as is common practice in connection with patching automobile tires. The centers, with the covers in place, are then placed in the heating apparatus or mold 10, and the whole is subjected to heat. The mold is heated in any suitable way and the covered centers are not subjected to any substantial pressure, the mold being used merely to confine the covered centers against the expansion tendencies of the heated gas or air within the center during the molding operation. The expansion of the air within the center will result 50 55

- in pressure at the surface of the ball and result in the two pieces forming the cover being firmly in place and the edges closely adhering together. The pieces forming the covers come to the user complete with cold cement along the edges as well as on one face of the covers, making it feasible for the recovering of centers away from the place of manufacture. The furnishing of ready-prepared covers to individuals, coaches and attendants suitable for recovering the centers, makes it only necessary to have a heating apparatus in order to recover the centers, and will result in a great savings in cost and operation.
- 15 Numerous variations may doubtless be devised

by persons skilled in the art without departing from the principles of my invention. I, therefore, desire no limitations to be imposed on my invention, except such as are indicated in the appended claim.

What I claim is:

Patch pack for tennis ball re-covering service comprising a plurality of shaped fabric blanks, congruently piled, and having the air-exposed edges which constitute the sides of the pile coated with a vulcanizable cement, the vulcanizing property of which is unimpaired by prolonged exposure to air, one face of each blank having a vulcanizable cementitious coating.
